UNITED STATES PATENT OFFICE.

DAVID W. MARTIN AND ROBERT F. THOMPSON, OF SCHENECTADY, NEW YORK, ASSIGNEES TO GENERAL ELECTRIC COMPANY, A CORPORATION OF NEW YORK.

ELECTROMAGNET.

1,253,409.

Specification of Letters Patent.

Patented Jan. 15, 1918.

Application filed January 23, 1917. Serial No. 144,031.

To all whom it may concern:

Be it known that we, DAVID W. MARTIN and ROBERT F. THOMPSON, citizens of the United States, residing at Schenectady, in the county of Schenectady, State of New York, have invented certain new and useful Improvements in Electromagnets, of which the following is a specification.

Our invention relates to alternating current electromagnets and has for its object the provision of means whereby the chattering of the movable member of the magnet due to alternations in the circuit are prevented in a simple and efficient manner.

It is well known that alternating current magnets are open to the objection that the movable member, in cases where it engages a stationary pole piece at the limit of its travel, chatters against the pole piece, by reason of the reduction in pull on the member as the voltage passes through zero. It has been found that if the movable member or core engages the stationary pole piece so that the parts are in contact throughout the engaging surfaces, the chattering will be greatly reduced, or may even disappear. In the case of a solenoid, for instance, if the moving core having a flat surface engages a flat stationary pole piece so that the two flat surfaces are in contact uniformly throughout the engaging area, the chattering will completely disappear, if the alinement is sufficiently good and the force tending to separate the parts is not too great.

It has heretofore been proposed to have one of the surfaces movable or yielding so that when the two members engage they will aline themselves. Such arrangements generally involve the use of a spring and are mechanically and otherwise objectionable for reasons which will be readily understood.

One of the objects of our invention is to provide means whereby the moving core or armature and the stationary pole piece aline themselves automatically upon engagement and the alinement is thereafter maintained. In one form of our invention we have one

of the engaging surfaces, as for instance, the stationary surface, movable in any plane so that it can properly aline itself with the moving surface when the two surfaces engage and we provide means whereby the alining surfaces may then be secured in an alinement position so that thereafter the surfaces will always be in proper alinement.

In the accompanying drawing illustrating one form of our invention Figure 1 is a side elevation partly in section of a no-voltage trip mechanism embodying our improvement; Fig. 2 is a detail of the self-alining pole-piece, and Fig. 3 is a diagram showing the connections and the switch mechanism in outline.

Referring to the drawings, it will be seen that we have shown our invention in connection with a low voltage trip mechanism of well known design, but it is in no sense limited to use in this particular application. In Fig. 1, therefore, 10 represents the winding for the switch which in this case is a no voltage winding connected across an A. C. supply circuit as shown in Fig. 3; 11 is the core of the solenoid which is shown as being of solid iron and 12 the pole-piece which the core engages at the limit of its movement. Trip lever 13 is pivoted at 14 and is operated by a spring 15 connected to the magnet frame at 16 to trip the switch locking mechanism 17 when released. The tripping lever is also weighted by means of the weight 17 pivoted to the lever at 18. The tripping lever is latched in its inoperative position shown in Fig. 1 by a bell crank lever 19 pivoted at 20. One end of the bell crank lever is pivoted to the core 11 by a slotted connection at 21, while the other end of the lever is provided with a roller 22 which engages the end of the trip lever 13 and holds it against the action of the spring and weight when the magnet is energized. All of this mechanism is well known and forms no part of our invention.

The upper end of the plunger 11, which is cylindrical in form, is flat and engages a flat surface of the pole piece 12. It has been

found in practice that if these two flat surfaces engage each other so as to make uniform contact throughout the surfaces, that the chattering due to alternating current in the winding 10 disappears. It is difficult, however, to get the two parts to aline themselves so that the surfaces will be in uniform engagement. In order to insure that these two flat surfaces will engage with a uniform contact, we have provided the universal joint arrangement shown in Fig. 2. The main body of the pole piece 23 is threaded into the magnet frame as shown in Fig. 1. The portion of the pole piece which is engaged by the core is separate from the main body but is mounted thereon for universal movement so that it may move freely in any plane and assume any position forced upon it by the flat surface of the plunger 11. This movable member 24 has a flat engaging surface 25 and a shank 26 extending through the main body of the pole piece. The portion having a flat surface has a spherical concave surface on its inner side to conform to the spherical convex surface 27 of the main body of the pole piece upon which it bears. The hole in the main body through which the shank 26 passes is considerably larger than the shank so as to permit free movement of the shank and a washer 28 having a spherical concave bearing surface conforming to the spherical convex surface upon the main body of the pole piece is held in place by nuts 29. The shank also has plenty of clearance from this washer.

As thus constructed, it will be seen that when the core 11 is first drawn upward into the solenoid, its upper face engages the flat face 25 of the movable portion of the pole piece, the nuts 29 being slackened off so as to permit free movement of the movable member and the washer. The surface 25 will thus aline itself accurately with the flat surface of the core. When the parts have alined themselves, the nuts 29 are taken up and the movable member secured in the alined position. This arrangement has been found very successful in bringing about this proper alinement and obviates the necessity for machine work after the parts are assembled. It has been found that when the alinement of the parts is accomplished the chattering of the plunger entirely disappears.

While we have described our invention as embodied in concrete form and as operating in a specific manner in accordance with the provisions of the patent statutes, it should be understood that we do not limit our invention thereto, since various modifications thereof will suggest themselves to those skilled in the art without departing from the spirit of our invention, the scope of which is set forth in the annexed claims.

What we claim as new and desire to secure by Letters Patent of the United States, is:—

1. An electromagnet comprising a magnet winding, an armature movable thereby, a pole piece engaged by the armature at the limit of its travel, means for causing alinement of these parts upon engagement and means for maintaining the alined condition after disengagement. 70

2. An electromagnet comprising a magnet winding, an armature movable thereby, a pole piece engaged by the armature at the limit of its travel, self-alining means associated with one of the engaging members and means for maintaining alinement after 80 disengagement. 75

3. An electromagnet comprising a magnet winding, an armature movable thereby, a self-alining stop engaged by the armature and means for locking the stop in place 85 after it has alined itself. 80

4. An electromagnet comprising a magnet winding, an armature movable thereby and having a flat engaging surface, a stop having a similar surface engaged by said armature at the limit of its travel and movable by such engagement so that the flat surfaces aline and means for locking the stop in its alined position. 90

5. An electromagnet comprising a solenoid, a core movable therein, a pole piece engaged by the core at the limit of its travel, means for causing the engaging surfaces to aline upon engagement and means for maintaining alined conditions after disengagement. 95 100

6. An electromagnet comprising a magnet winding, an armature movable thereby and having a flat engaging surface, a flat pole piece engaged by the armature at the limit of its travel, self-alining means associated with one of the engaging members for causing the two flat surfaces to contact uniformly throughout the engaging area, and means for maintaining the alined position 110 after disengagement. 105

7. An electromagnet comprising a magnet winding, an armature movable thereby and having a flat engaging surface, a pole piece having a flat engaging member mounted thereon for universal movement so as to insure uniform contact with the armature, and means for locking the member in the position which it assumes upon engagement. 115

8. An electromagnet comprising a magnet winding, an armature movable thereby, a pole piece engaged by the armature at the limit of its travel, a self-alining universal joint associated with one of the engaging members, and means for securing the universal joint in place after it has alined itself. 120 125

9. An electromagnet comprising a magnet winding, an armature movable thereby and having a flat engaging surface, a pole piece having a spherical convex surface and an 130

engaging member having a flat surface, the
said engaging member having a spherical
concave surface adjustable on the spherical
convex surface on the pole piece for causing
5 a self-alinement of the flat surfaces of the
armature and of the engaging member, and
means for locking the engaging member in

place after it has alined itself with the
armature.

In witness whereof, we have hereunto set 10
our hands this 22nd day of January, 1917.

DAVID W. MARTIN.
ROBERT F. THOMPSON.
